UNITED STATES PATENT OFFICE.

MAX M. COHN, OF PIEDMONT, CALIFORNIA.

SLOTTED CARTON.

1,148,758.

Specification of Letters Patent.

Patented Aug. 3, 1915.

Application filed December 9, 1914. Serial No. 876,286.

To all whom it may concern:

Be it known that I, MAX M. COHN, a citizen of the United States, residing at Piedmont, in the county of Alameda and State 5 of California, have invented new and useful Improvements in Slotted Cartons, of which the following is a specification.

This invention relates to a container and dispensing device for paper towels and 10 other articles.

The object of this invention is to provide a simple, cheap, practical carton for holding and dispensing sheet material, like paper towels, which will have the desired 15 reinforces at otherwise weak points, and which carton, when emptied, may be thrown away; the filled container being sold in the first case as an original package.

The invention consists of the parts and 20 the construction and combination of parts as hereinafter more fully described and claimed, having reference to the accompanying drawings, in which—

Figure 1 is a perspective front view of a 25 filled carton. Fig. 2 is a perspective rear view of same. Fig. 3 is a detail perspective front view of one corner of a finished carton. Fig. 4 is a plan view of a carton blank. Fig. 5 is a detail perspective rear 30 view of one corner of a finished carton.

The invention resides in the cutting and folding of a sheet of cardboard or the like to form a carton A adapted to contain a stack of paper towels, or the like, so arranged within the container that there will 35 always be projected an end or edge 2 of a towel through the withdrawal slot 3; the withdrawing of one towel through the slot automatically positioning the leading end 40 of a succeeding towel.

The present invention has nothing to do with the arrangement of the towels, except that the towels are stacked so that they stand on edge in the container with the 45 leading end always adjacent to the slot 3; one of the purposes being to provide a narrow, shallow package; in other words, a package containing the maximum number of towels in a minimum space.

The carton is formed from a single piece 50 of cardboard, scored and cut to provide a back panel 5 provided with integral end panels 6, a top panel 7, and a bottom panel 8. The bottom panel 8 is contained in a succession of panels 9, 10 and 11 of ap-

proximately the same length and width as the bottom panel 8, so that when overfolded and shaped into the carton they will provide a reinforced, three-ply front wall with smooth edges below the withdrawal slot 3. 60 Attached at right angles to the ends of one of the intermediate panels, as 9, are the filler pieces 12 which are substantially the same width as the end panels 6 and of a length approximately equal to the width of 65 the three panels 9, 10 and 11. The end panels 6 have extension flaps 15, which flaps are provided, at their lower ends, with the panel extensions 16 and 17; the length of a panel 16 being approximately equal to the 70 width of the intermediate panel 9 and the panel 17 of indefinite length as it is only designed to form a filler and reinforce to the bottom, as later described.

The end panels 6 have end flaps 18 designed as interlocking members. Top panel 7 has a front panel extension 20 with interlocking end flaps 21 and 22; the flaps 22 co-operating with incisions 23 made in the back and near the ends of the back panel 5. 80 The panel section 20 forms a front of the completed carton above the slot 3. The carton is assembled in the following manner: Panels 11, 10 and 9 are folded, one on the other, to form a three-ply arrangement and 85 then made to stand at right angles to the bottom panel; the panel 8 then being turned up from the back 5 to stand at right angles thereto. At the same time the end pieces 12 are turned in at right angles to the panels 90 11, 10, 9 and to panel 8, lying inside of the end panels 6. End panels 6 are then folded up against the pieces 12 and the tabs 18 are inserted into the little pockets formed between the lower edges of the end pieces 12 95 and the bottom 8. Next the flaps 15, attached to the end panels 6, are folded inwardly over the spacer pieces 12 and the parts 16 and 17 bent back to permit their being received into the trough-like spaces 100 formed by the parts 5, 8 and 9. The carton is then filled with paper towels. Next the top 7 is folded up against the three-ply end walls formed by the contiguously lying parts 6, 12 and 15 and the front panel 20 105 brought down over the front of the carton to form the slot 3 in conjunction with the overfolded members 11, 10 and 9. Sections 21 are then folded backwardly across the ends of the carton and the tabs 22 are in- 110

serted into the slits 23. The completed package is thus ready for distribution to the trade.

If it is desired to provide a temporary hanger for the package at the top of the carton, along the scoring 25, where the top panel 7 joins the back 5 there may be made a couple of slits 26 to receive the hanger ends 27 of a suitable cardboard hanger 28.

By this method of construction and reinforcement a substantial and durable carton, suitable for the purposes contemplated, may be made of cheap material and at very small expense. It is around the slot 3 that the heaviest strain and wear comes on this device and it is for that reason that the method of overfolding described is resorted to. It is to be noted that the bottom edge and end edges of the withdrawal slot 3 are not only made up of a number of plies of material, but the overfolding gives smooth round edges not liable to be torn or mutilated in handling.

Having thus described my invention, what I claim and desire to secure by Letters Patent is—

1. A carton for paper towels and the like made from a single strip of cardboard folded to form a container with a withdrawal slot disposed in a wall thereof, the said slot being permanently defined by the folded ends of the strip of the cardboard when said ends are secured in position.

2. A carton of the character described comprising a container body having a front sectional wall, the bottom section of which being normally fixed and the top section being flexibly joined to the top of the container for opening to permit of the insertion of articles into the container and spaced from the bottom section to provide a withdrawal slot through which the articles may be removed.

3. A slotted carton made from a blank, which blank consists of a back panel, and top, bottom and end panels flexibly connected to the back panel, said bottom and end panels each provided with overfolded reinforcing panel members, the top panel carrying a front panel portion coöperating with a panel portion attached to the bottom panel portion to provide a slot when the parts are assembled.

4. A blank for a slotted carton, consisting of a back panel portion with flexibly connected top, bottom and end panels, the bottom panel provided with three successive panel members adapted to be overfolded, one upon the other, one set of overfolding panels containing a spacer panel to coact with the end panels and reinforce the latter, the end panels having each an interlocking tab coöperating with the bottom panel and overfolding spacer members, said top panel having a front panel section with

flexible end pieces to interlock with the back panel and form the carton, substantially as described.

5. A structure of the character described comprising a body having spaced slits and a retaining tab offset therebetween, and a hanger made from a single strip of cardboard with spaced hanger members projecting out through the slits of the body, the retaining tab of the latter engaging over the hanger to retain the hanger members projected.

6. A blank for a slotted carton including a back panel portion with flexibly connected top, bottom and end panels, the bottom panel provided with a plurality of successive panel members adapted to be overfolded one upon the other, one overfolding panel containing spacer panels to coact with the end panels and reinforce the latter.

7. A blank for a slotted carton including a back panel portion with flexibly connected top, bottom and end panels, the bottom panel provided with a plurality of successive panel members adapted to be overfolded one upon the other, the end panels each having an interlocking tab coöperating with the bottom panel and overfolding spacer members.

8. A blank for a slotted carton including a back panel portion with flexibly connected top, bottom and end panels, the bottom panel provided with a plurality of successive panel members adapted to be overfolded one upon the other, said panel members being folded in angular relation with the bottom panel to form a bottom front panel section, and the top panel having a top front panel section with flexible end pieces to interlock with the back panel, substantially as described.

9. A blank for a carton including a back panel with flexibly joined bottom and end panels, the bottom panel provided with a flexibly connected front panel section having a spacer panel to coact with and reinforce the end panel, the latter carrying a spacer member folding over the spacer panel and interlocking with the latter and front panel section, substantially as described.

10. A blank for a carton including a back panel with flexibly joined bottom and end panels, the bottom panel provided with a flexibly connected front panel section having an angularly disposed spacer panel to coact with and reinforce the end panel, the latter carrying an interlocking tab coöperating with the bottom panel and a spacer member folding over the spacer panel, substantially as described.

11. A carton blank comprising a back panel with flexibly joined top, end and bottom panels, each end panel having an interlocking tab and reinforcing member coöperating with the bottom panel, and the top panel having a front panel section foldable down over the front and provided on its

ends with locking tabs adapted to be folded backwardly across the end panels to interlock with the back panel.

12. A carton blank comprising a back panel portion provided with top, bottom and end panels adapted to be folded in angular relation to the back to form a container, spacer panels for holding the bottom panel in position and reinforcing the end panels,
- 10 the latter each having an interlocking tab coöoperating with the bottom panel and a spacer member foldable over the adjacent spacer panel to retain the latter in position,

and the top panel having joined to its forward edge a front panel section provided on its ends with locking tabs foldable backwardly across the end panels and adapted to be secured to the back panel. 15

In testimony whereof I have hereunto set my hand in the presence of two subscribing 20 witnesses.

MAX M. COHN.
